NESOTA, A CORPORATION.

GRAPPLE.

1,093,834.

Specification of Letters Patent. Patented Apr. 21, 1914.

Application filed October 3, 1912. Serial No. 723,755.

To all whom it may concern:

Be it known that we, OLIVER CROSBY, ED-
WARD A. WILHELM, and HARRY L. BRINK, of
St. Paul, Ramsey county, Minnesota, have
5 invented certain new and useful Improve-
ments in Grapples, of which the following is
a specification.

Our invention relates to that type of grap-
ples, shown and described in our pending
10 application for Letters Patent of the United
States, No. 655,778, filed October 20, 1911.

The object of our present invention is to
adapt this type of grapple for unloading
15 wagons of cane or similar material where
there is a comparatively small quantity of
the cane, and where it would be wholly im-
practicable to use the large, heavy grapple
of our application above referred to. The
20 large grapple is designed for handling car-
loads of cane or where it is collected in a
storage pile, and to avoid the necessity of
providing a smaller, lighter grapple, or un-
weaving the cables of the large grapple for
25 operating a smaller one, we have adapted the
large grapple for handling both the large
and light loads.

A further object is to allow the grapple to
be left on the ground and the blocks pulled
30 away from it, the derrick roped to handle
these grapples being used for other purposes
than handling the cane.

The invention consists generally in vari-
ous constructions and combinations, all as
hereinafter described and particularly point-
35 ed out in the claims.

In the accompanying drawings forming
part of this specification, Figure 1 is a side
elevation of a grapple embodying our inven-
tion, showing it adapted for handling car-
40 loads of cane, or from a storage pile. Fig.
2 is a detail view showing the upper portion
of the grapple, detached from the hooks
without unweaving the operating cables, and
45 ready for handling light loads of cane or
other material. Fig. 3 is an end view of the
apparatus shown in Fig. 2. Fig. 4 is a de-
tail view illustrating the means for connect-
ing the sling shaft to the sheave blocks.

In the drawing, 2 represents the shaft of
50 the cane grapple and 3 a series of grapple
hooks mounted thereon, and adapted to

swing toward and from one another, all as
set forth in the above mentioned application.
4 is a beam, and 5 represents bails con-
nected to the grapple hooks and pivoted at 6 55
to the beam 4. Upon this beam 4 sheave
blocks 7 are mounted, and arranged to pro-
ject above and below the beam, and provided
with sheaves 8 and 9, sheave 9 above the
beam and sheave 8 below. Opening cables 60
10 have running connections with the
sheaves 9 for raising the beam, lifting the
bails and separating the grapple hooks.
Blocks 11 having sheaves 12 are provided
15 between the grapple hooks and are secured 65
to the shaft 2, by means of straps 13 and
links 14. The straps 13 are preferably se-
cured to the lower portions of the blocks and
depend on each side of the shaft 2, and the
links 14 are pivotally connected at one end 70
to one of the straps and have holes 15 in
their opposite ends to receive bolts 17 which
pass therethrough, and through holes 16 in
the other strap. The links thereby close the
75 opening between the straps and support the
shaft 2, concave seats 18 being preferably
provided in the upper edges of said links
upon which the shaft 2 rests.

When the shaft 2 is in the position shown
in Fig. 1 and is secured to the blocks 11, the 80
grapple is adapted for handling large quan-
tities of cane, either in a storage pile or on
cars, as may be desired. In case, however, a
wagon load of cane is brought to the mill or
other point the large grapple cannot be suc- 85
cessfully used for unloading it, being much
too heavy and bulky for the purpose. We,
therefore, remove the bolts 17 and detach the
shaft 2 and the grapple hooks entirely from
the blocks 11, then disconnect the bails 5 90
from the beam 4, and the blocks and beam
thus become entirely detached from the grap-
ple hooks, as shown in Fig. 2. We then sub-
stitute in place of the shaft 2 a shaft 19,
having collars 20 at its ends to prevent end- 95
wise movement and provide at intervals
loops 21 having hooks 22 thereon. These
hooks are adapted to engage slings 23 pref-
erably in the form of chains, which are
adapted to pass around the load of cane on a 100
wagon and lift the load from the wagon
when the cables are operated. When the

wagons have been unloaded the shaft 19 may be disconnected from the blocks and the blocks and beam may then be attached to the large grapple hooks. The operation of adapting the large grapple for handling cane on wagons or on cars can be easily and quickly performed and without the necessity of unweaving the operating cables, an operation which obviously would require considerable time and labor. We are thus able to make one large grapple perform two distinct functions and adapt it for a double use, and thereby provide a decided improvement over grapples of this kind as ordinarily constructed, where it would be necessary to unweave the cables and connect them to a smaller grapple, or provide two distinct grapples.

Obviously when the grapple hooks have been detached from the sheave blocks and operating cable, the device with the slings attached thereto is capable of a variety of uses.

The upper portions of the sheave blocks 11 are provided with bars 24, having horizontal flanges 25, and the lower ends of the blocks 7 have horizontal flanges 26 thereon which are adapted to rest on the flanges 25 when the boxes are brought together for handling light loads, and we prefer to secure the flanges 25 and 26 together by means of bolts 27, thereby holding them in rigid relation to one another when used with the sling shaft.

We do not confine ourselves in the use of the sling grapple to the handling of small quantities of cane, nor do we confine ourselves to the particular manner shown for detachably mounting the grapple shaft on the sheave blocks, as in various ways this connection may be modified and still be within the scope of our invention.

We claim as our invention:—

1. A grapple comprising a beam, upper sheave blocks mounted on said beam, lower sheave blocks disposed below said first named blocks and having seats to receive said first named blocks, means for rigidly securing said upper and lower blocks together, cables having running connections with said blocks, a shaft and cane supporting means thereon, and means for temporarily clamping said shaft on said lower blocks.

2. A grapple comprising a beam, upper sheave blocks mounted on said beam, lower sheave blocks, means for temporarily securing said upper and lower blocks together, cables having running connections with said blocks, a shaft, slings carried by said shaft and adapted to pass around a load of cane, means for temporarily clamping said shaft on said lower blocks.

3. A grapple comprising a beam; upper sheave blocks mounted on said beam, lower sheave blocks, cables having running con-

nctions with said sheave blocks, a shaft, cane engaging means carried thereby, straps mounted on said lower blocks and spaced apart to receive said shaft, and links pivotally connected with one of said straps and having means for connection with the other strap, said links temporarily supporting said shaft upon said lower blocks.

4. A grapple comprising a cross head, a sheave block mounted therein and having an upper and a lower sheave, a second sheave block arranged transversely of said first named block and having means for securing it thereto, and sheaves mounted side by side in said second named block, cables having running connections with the sheaves of said blocks, and a cane sling having means for connection with said second named block.

5. A cane lifting device comprising a cross head, a pair of sheave blocks mounted thereon, a second pair of sheave blocks arranged side by side beneath said first named blocks and having means for securing them respectively to said first named blocks, cables having running connections with the sheaves of said blocks, and cane lifting means for connection with said second named blocks.

6. A cane lifting device comprising a sheave block, and sheaves mounted one above another therein, a second sheave block having sheaves arranged side by side therein, means for securing said blocks together, and cane lifting means and means for temporarily attaching it to said second named block.

7. A grapple comprising upper sheave blocks, lower sheave blocks, means for temporarily securing said upper and lower blocks together, cables having running connections with said blocks, a shaft having means for temporarily securing it to said blocks, and cane slings carried by said shaft.

8. A grapple comprising sheave blocks and cables having running connections therewith, a shaft, cane engaging means carried thereby, straps mounted on said blocks and spaced apart to receive said shaft, links pivotally connected with one of said straps and having means for connection with the other strap, said links temporarily supporting said shaft upon said blocks.

9. A combined grapple and cane lifting means comprising a cross head, a pair of sheave blocks mounted thereon, a second pair of sheave blocks having means for temporarily securing them to said first named blocks, cables having running connections with the sheaves of said blocks, a shaft and cane slings carried thereby, clamping means for temporarily securing said shaft to said second pair of sheave blocks, the removal of said shaft allowing the substitution of a grappling shaft and fingers therefor.

10. A grapple comprising a beam, a flanged sheave block mounted thereon, a second flanged sheave block adapted to be seated against the flanges of said first named block, bolts passing through said flanges for temporarily securing said blocks together, cables having running connections with said blocks, and a shaft detachably connected with said second block.

In witness whereof, we have hereunto set 10
our hands this 27th day of September 1912.
